UNITED STATES PATENT OFFICE.

LLOYD C. EPPLER, OF GROTON, NEW YORK, ASSIGNOR TO AIRDY CORPORATION, OF GROTON, NEW YORK, A CORPORATION OF NEW YORK.

COIN-OPERATED RECIPROCATING TIME SWITCH.

Application filed March 19, 1923. Serial No. 626,111.

To all whom it may concern:

Be it known that I, LLOYD C. EPPLER, a citizen of the United States, and resident of Groton, in the county of Tompkins and State 5 of New York, have invented certain new and useful Improvements in Coin-Operated Reciprocating Time Switches, of which the following is a specification.

The main object of this invention is to 10 provide a simple apparatus in which a coin operated mechanism is adapted to close an electric circuit and maintain the same in closed position throughout the lapse of a predetermined period of time. The apparatus 15 is specially designed for closing an electric motor circuit but the apparatus is capable of use in a variety of relations and the invention therefore is not limited with respect to use.

Another important object of the invention 20 is to provide means whereby the motor drives means for operating the switch to open the motor circuit after a predetermined time and reset the apparatus for actuation by the insertion of another coin.

The invention is designed especially for 25 use in connection with a hand drying machine in which an electric motor is arranged to drive a fan or blower, the air from the said fan passing over a heating coil and being then discharged through a nozzle, it being desirable with this class of machines to operate them for a predetermined time and then automatically open the motor circuit, the switch operating parts being left 35 in position to be again actuated by the insertion of another coin.

As shown in the drawings and described 40 herein the invention consists of a coin operated means for tripping a locking dog to permit the switch to snap into the circuit closing position. The motor fan operates for a predetermined time and through a speed reduction gearing forces the switch into its open position and resets the coin operating 45 means for actuation by the insertion of another coin.

In the drawings, Fig. 1 is a side elevation 50 of the switch operating mechanism connected to the shaft of a motor blower, the blower casing and the motor casing being shown partly in sectional view to more clearly show the construction;

Fig. 2 a detail end elevation of the coin

operated means for releasing the holding 55 dog;

Fig. 3 a detail sectional view on the line 3—3 of Fig. 1;

Fig. 4 a detail vertical sectional view showing the coin operated means releasing 60 the holding dog;

Fig. 5 a vertical sectional view showing the holding dog released and the switch in its circuit closing position;

Fig. 6 a detail vertical sectional view 65 showing the operation of resetting the coin operated releasing means;

Fig. 7 a detail sectional view illustrating the beginning of the switch opening movement;

Fig. 8 a detail vertical sectional view showing the parts near the end of their switch opening movement;

Fig. 9 a detail cross sectional view on the line 9—9 of Fig. 8;

Fig. 10 a detail sectional view on the line 10—10 of Fig. 1; and

Fig. 11 a detail sectional view of the fan casing showing the heating coil in the discharge nozzle.

Referring to the various parts by numerals, 1 designates a fan or blower casing in which is mounted a rotary fan 2. The blower casing is provided with a discharge nozzle 3 through which the air is driven by 85 the fan. Usually an electric heating coil 3^a is arranged in the discharge nozzle, said coil being of any suitable form and usually in circuit with the motor so that when the motor circuit is completed the heating coil will 90 be energized. The fan 2 is rigidly connected to the end of a shaft 4 of the electric motor 5. This motor is enclosed in a casing 6 rigidly connected to the side of the fan casing. The fan casing, opposite the motor 95 casing, is open as illustrated at 7 in Fig. 1. It is obvious that when the motor is energized the fan will be rotated and a blast of air will be driven through the nozzle 3 and over and through the heating coil 3^a, the fan operating to draw air in through the opening 7.

Rigidly secured to the side of the fan casing, opposite the motor casing 6, is a bracket 8 having a substantially horizontal arm 9 from which depends shaft supporting arms. Suspended from the bracket 8 is a box 10 in which is arranged a double reduction worm gearing comprising a high

speed shaft 11 and a low speed shaft 12. The reduction worm gearing is interposed between these two shafts. It is obvious that the worm gearing may be so arranged as to secure the desired reduction in speed between the high speed shaft 11 and the low speed shaft 12. The high speed shaft 11 is mounted in suitable bearings in the box 10 and in the bracket 8, and as illustrated, the bracket 8 serves as a means for suspending the reduction gearing box 10. It is obvious, however, that the reduction gearing box may be secured in any suitable manner and also that the high speed shaft may be provided with any suitable form of bearings. The high speed shaft 11 is in substantial axial alignment with the motor shaft and is provided at its inner end with a cross pin 13 which is adapted to loosely engage the arms 14 of a yoke secured to the fan or motor shaft 4. The end of the high speed shaft carrying the cross pin extends into the fan casing and is loosely engaged with the yoke within the casing. The purpose of this loose connection is to avoid the necessity of accurately aligning the high speed shaft with the motor shaft and also to permit the parts to be readily assembled. It is obvious that the cross pin 13 must engage the arms 14 of the yoke on opposite sides in order that the high speed shaft will be driven by the motor shaft. The box containing the reduction worm gearing is preferably filled with some suitable form of lubricant to insure the easy running of the gears. On one end of the low speed shaft 12 is secured a crank 15, said crank being connected to the switch opening and closing devices as will be hereinafter described.

The switch shown in the drawings, for opening and closing the motor circuit, is of a well known construction. The contact arms are carried by a rocking bar 17 mounted in a suitable rigid frame 18. The bar 17 is rocked through a rocking frame 19 which is mounted in the frame 18 and is connected by push links 20 to a rocking operating lever 21. The lever 21 is pivoted in the frame 18. As illustrated in the drawings the contact arms are thrown into position to close the motor circuit when the rocking lever 21 is moved upwardly, as shown in Fig. 5 of the drawings. When the rocking lever 21 is forced downwardly to the limit of its movement the contact arms are snapped to their "off" position to open the motor circuit, as illustrated in Fig. 1 of the drawings. This is a well known type of switch and it is thought unnecessary to illustrate the details of the construction thereof. The frame 18 carries a plate 22 on which are mounted knife-blade stationary contacts 23 which are designed to be engaged by the contact arms 16. The contacts 23 are insulated from the plate 22 and the motor cir-

cuit wires 24 are connected to them. The switch, of course, is spring operated so that it has a quick snap movement both in closing and opening the motor circuit. The switch as a whole is supported in the frame 70 of the drying machine by means of a bracket 25, said bracket being provided with a horizontal portion 26. It is obvious, however, that the switch may be supported in the machine in any suitable manner. 75

A switch operating pitman 27 is connected at its upper end to a crank pin 28 mounted in the end of the crank 15. The lower end of the pitman is pivoted to the free end of the rocking lever 21 so that a reciprocating movement of the pitman will operate to move the switch to its open or closed position. The crank pin 28 is provided with a square operating block 29. The pitman is tubular and substantially rectangular in cross section. Near its upper free end it is slotted vertically at 30, said slot being formed in opposite side walls thereof. The operating block 29 extends through the pitman and fits snugly in the slot 30, engaging the walls of said slot, as clearly illustrated in the drawings. The pitman is held on the operating block by means of a washer 31 secured to the projecting end of the crank pin 28, said washer also serving to hold the operating block in the pitman. The operating block slides freely in slot 30 so that the pitman may move vertically under the influence of the switch closing spring and independently of the crank 15. The horizontal portion 26 of the switch supporting bracket extends through the slots in the pitman and serves as a rigid stop and support for the lower end of the switch closing spring 32, said spring being mounted within the pitman and the upper end thereof engaging a rigid inwardly turned lip 33, said lip serving, when the pitman is forced downwardly, to compress the spring 32 and thereby set it for the switch closing operation. The pitman is vertically slotted for the passage of the arm 26 of the switch supporting bracket to permit the pitman to reciprocate, as shown clearly in Fig. 5 of the drawings. 105

Pivoted near the upper free end of the pitman is a locking dog 34 whose upper end extends within the pitman and is adapted to be engaged by the operating block 29. A spring 35 normally forces the upper end of the locking dog into the path of the operating block; and the upper end of said dog is notched at 36 to receive the operating block. The upright wall of the notch 36 is adapted to engage the side of the operating block and thereby form a stop to limit the inward swinging movement of the locking dog. The locking dog 34 is extended below its pivot to form a releasing arm 37 which lies along side of the pit- 110 115 120 125 130

man, said releasing arm being normally thrown outwardly away from the pitman by the spring 35. Mounted on the arm 26, and in position to engage the releasing arm 37 is a trip device 38. This trip device consists of a channel frame 39 in which reciprocates a trip 40, said trip carrying a roller 41 which is adapted to be pressed into engagement with the releasing arm 37. The trip 40 carries a transverse pin 42 which operates in elbow slots 43 formed in the side walls of the frame 39. Connected to the pin 42 is a spring 44, said spring extending toward the pitman and being connected to a rigid pin 45 carried by the frame 39. The trip device 40 is slotted at 46 through which the pin 45 extends and which permits the trip to have a movement toward the pitman under the influence of the spring 44. The trip device is locked in its retracted position by the pin 42 dropping down in the vertical portion of the elbow slot 43. When the trip device is lifted, as will be hereinafter described, the pin 42 is raised into the longer horizontal portion of the slot 43 and the spring 44 will then cause it to move toward the pitman and into engagement with the arm 37. The spring 44 tends to pull the pin downwardly into the vertical portion of the elbow slot and thereby latch the trip device in its retracted position. In the channel frame 39, below the trip device 40, is mounted a short rock shaft 47, said shaft being mounted on sensitive anti-friction bearings so that it will rock readily. Where said shaft passes under the end of the trip device it is flattened or squared to form a cam surface 48 which normally engages the under side of the trip device so that when said shaft is rocked the cam face 48 will lift the trip device and free the pin 42 from the shoulder in the elbow slot 43. Mounted in the rock shaft is a long arm 49 which carries at its free end a coin cup 50, said cup being disposed in a suitable position in the machine frame to receive a coin. It is manifest that the machine will be provided with a coin chute or slot adjacent the coin cup 50. The arm 49 is carried through the rock shaft and its end opposite the coin cup is provided with a counter balance weight 51, said weight acting to normally hold the coin cup in position to receive a coin. A stop 52 is adapted to be engaged by the counterweight when the coin cup is in its normal position.

In Fig. 1 the switch is shown in open position with all the parts at rest. To close the switch a coin is dropped into the coin cup 50. The weight of the coin will depress the cup 50 and rotate the rock shaft 47. The cam face 48 will lift the trip device 40 and free the pin 42 from the shoulder of the elbow slot. The spring 44 will

70 snap the trip device toward the pitman and cause the roller 41 to force the releasing arm inwardly toward the pitman as shown in Fig. 4. This will free the locking dog from the operating block and the pitman 75 will be thrown up by the spring 32. The slot 30 will permit the pitman to move upwardly and the upward movement of the pitman will rock the lever 21 and throw the switch to its closed position. This operation is clearly illustrated in Fig. 5. The motor circuit is now closed and the crank 15 starts to move in the direction indicated by the arrow in Figs. 5 and 6. The movement of the crank will swing the upper end 80 of the pitman toward the trip device and will engage the roller 41, thereby forcing the trip device against the tension of the spring 44 until the pin 42 is snapped down into the vertical elbow portion of the slot 85 43 thereby latching the trip device in its retracted position. The crank will continue its movement until it has reached the top or outer end of the slot 30. When it has reached the outer end of the slot 30 the 90 locking dog will snap in under the operating block, as shown in Fig. 7. The continued rotation of the crank 15 will now carry the pitman downwardly, as shown clearly in Fig. 8. The downward movement 95 of the pitman will recompress the spring 32 and when the pitman has reached the limit of its downward movement the lever 21 will have been moved on its pivot sufficiently to snap the switch into its open position and the motor will be stopped. The timing mechanism is so arranged that the motor will be in operation during one complete revolution of the crank 15 so that when the parts have been restored to the position 100 shown in Fig. 1, the motor will be stopped and all the parts will be in position for another operation by the insertion of another coin in the coin cup 50.

105 What I claim is:

110 1. A time switch for an electric motor comprising a motor, a reduction gearing including a high speed shaft and a low speed shaft, means for driving the high speed shaft from the motor shaft, a rocking switch, a spring tending to move said switch to its closed position, means for locking said switch in its open position, means for releasing the said switch locking means, and a bar operated by the rotation of the low 115 speed shaft to force the switch into its open position, said switch opening bar resetting the switch closing spring and the means for releasing the switch locking means.

120 2. A time switch for an electric motor comprising a motor, a reduction gearing including a high speed shaft and a low speed shaft, means for driving the high speed shaft from the motor shaft, a rocking switch, a spring tending to move said 125 130

- switch to its closed position, a dog for locking said switch in its open position, means for releasing the said switch locking dog, and a bar operated by the rotation of the 5 low speed shaft to force the switch into its open position, said switch opening means resetting the locking dog, the switch closing spring and the means for releasing the switch-locking dog.
- 10 3. A time switch for an electric motor comprising a motor, a reduction gearing including a high speed shaft and a low speed shaft, means for driving the high speed shaft from the motor shaft, a rocking switch 15 lever, a pitman connected to said lever, a crank mounted on the low speed shaft and operating in a slot in the pitman, a pivoted locking dog to lock the crank to the pitman, a switch closing spring adapted to be placed under tension by the rotation of the crank, a means to release the locking dog from the said crank and thereby permit the switch closing spring to move the pitman and rock the switch lever to closed 20 position, and means whereby the rotation of the crank will cause the locking dog to re-lock the crank to the pitman.
4. A time switch for an electric motor comprising a motor, a reduction gearing including a high speed shaft and a low speed shaft, means for driving the high speed shaft from the motor shaft, a rocking switch lever, a pitman pivoted at its lower ends 25 to said lever the other end being free to swing, said pitman being slotted longitudinally at its free upper end, a crank mounted on the low speed shaft and operating in the slot in the pitman, a pivoted locking dog carried by the pitman and adapted to lock 30 the crank to the pitman when the crank is in the upper end of the said slot, a switch closing spring adapted to be placed under tension when the pitman is moved downwardly by the crank, a means to release the locking dog from the crank and thereby permit the switch closing spring to rock the switch lever to its closed position, and means whereby the locking dog will relock 35 the crank to the pitman when the crank reaches the upper part of the slot in the pitman.
5. A time switch for an electric motor comprising a motor, a reduction gearing including a high speed shaft and a low speed shaft, means for driving the high speed shaft from the motor shaft, a rocking switch lever, a pitman pivoted at one of its ends 40 to said lever the other end being free to swing, said pitman being slotted longitudinally at its free end, a crank mounted on the low speed shaft and operating in the slot in the pitman, a pivoted locking dog carried by the pitman and adapted to lock 45 the crank to the pitman when the crank is in the outer end of said slot, a switch closing 45
- spring adapted to be placed under tension when the pitman is moved by the crank, a means to release the locking dog from the crank to permit the switch closing spring to move the pitman and thereby rock the 50 switch lever to its closed position, and means whereby the locking dog will re-lock the crank to the pitman when the crank reaches the outer end of the slot in the pitman.
6. A time switch mechanism comprising a reduction gearing including a high speed shaft adapted to be driven by a motor and a low speed shaft, a switch shiftable to open and closed positions, a pitman, an operative connection between said switch and the pitman, a crank mounted on the low speed shaft, a pivotal and slidable connection between said crank and pitman, means to automatically lock said pitman and crank against relative sliding at their 55 said pivotal connection, a switch closing spring adapted to be placed under tension by the rotation of the crank, means to release said crank and pitman locking means and thereby permit said switch closing spring to move the pitman longitudinally relatively to the crank and shift the switch to closed position, and means whereby the rotation of the crank will cause the said locking means to relock the crank and pitman together and cause the switch to be opened and the spring to be re-tensioned by the continued rotation of the crank.
7. A time switch mechanism for an electric motor comprising a reduction gearing including a high speed shaft adapted to be driven by a motor and a low speed shaft, a switch shiftable to open and closed positions, a pitman operatively connected to 60 said switch, a crank carried by said low speed shaft, a pivotal and slidable connection between said crank and pitman, means for locking the pitman against sliding relatively to the crank, means tending to shift the switch to closed position, settable pitman releasing means adapted to be tripped for releasing said locking means and permit said switch closing means to slide the pitman longitudinally to close the switch, means whereby the rotation of the crank 65 will cause the said locking means to re-lock the crank and pitman together and cause the switch to be opened by the continued rotation of the crank the said pitman releasing means being adapted to be re-set by the movement of the pitman to switch opening position.
8. A time switch mechanism comprising a reduction gearing including a high speed shaft adapted to be driven by a motor and a low speed shaft, a crank carried by the said low speed shaft, a switch shiftable to open and closed positions, a pitman, an operative connection between said switch 70 75 80 85 90 95 100 105 110 115 120 125 130

- and pitman, a pivotal and slidale connection between said pitman and crank, means carried by the pitman to automatically lock the pitman against sliding movement relatively to the crank at said pivotal connection, means tending to shift the switch to closed position, means for releasing said crank-and-pitman-locking means to permit said switch closing means to move the pitman longitudinally and close the switch, and means whereby the rotation of the crank will cause the said locking means to relock the crank and pitman together and cause the switch to be opened by the continued rotation of the crank.
9. A time switch mechanism for an electric motor comprising a reduction gearing including a high speed shaft adapted to be driven by the motor and a low speed shaft, a switch shiftable to open and closed positions, switch shifting means connecting the low speed shaft and the switch; a spring tending to close the switch, means adapted to operatively connect said shifting means to the low speed shaft and prevent the spring from closing the switch, settable means adapted to be tripped to release said shaft connecting means and permit the spring to close the switch and start the motor, means to automatically re-connect the low-speed shaft to said switch shifting means upon a predetermined rotation of the low speed shaft, whereby the switch will be opened and the spring retensioned by a further rotation of the low speed shaft, the said settable releasing means being adapted to be automatically reset by the switch shifting means upon the switch opening movement thereof.
- In testimony whereof I hereunto affix my signature.

LLOYD C. EPPLER.
